C. L. DUNHAM.

UNDERREAMER.

APPLICATION FILED SEPT. 12, 1918.

1,304,167.

Patented May 20, 1919.

UNITED STATES PATENT OFFICE.

CHARLES L. DUNHAM, OF PENNSBORO, WEST VIRGINIA.

UNDERREAMER.

1,304,167.

Specification of Letters Patent.

Patented May 20, 1919.

Application filed September 12, 1918. Serial No. 253,805.

To all whom it may concern:

Be it known that I, CHARLES L. DUNHAM, a citizen of the United States, residing at Pennsboro, in the county of Ritchie and State of West Virginia, have invented certain new and useful Improvements in Underreamers, of which the following is a specification.

This invention relates to an under-reamer 10 for oil wells but it is to be understood that the device is designed for any purpose wherein it is found applicable and the invention has for its object to provide, in a manner as hereinafter set forth, an under-reamer which is simple in its construction and arrangement, formed of few parts, readily assembled, efficient in its use and comparatively inexpensive.

With the foregoing and other objects in view this invention consists of the novel construction, combination and arrangement of parts, as hereinafter more specifically described and illustrated in the accompanying drawings, wherein is shown an embodiment 25 of the invention, but it is to be understood that changes, variations and modifications can be resorted to which come within the scope of the claim hereunto appended.

In the drawings wherein like reference 30 characters denote corresponding parts throughout the several views:

Figure 1 is an elevation of an under-reamer, partly broken away, in accordance with this invention.

Fig. 2 is a vertical sectional view thereof extended into a casing.

Fig. 3 is an inverted plan.

Referring to the drawings in detail 1 denotes a shank and 2 the body portion of the 40 reamer, the latter is formed with a horizontal opening 3, which extends in the direction of the length thereof. The body portion 2 has a lengthwise slot 4, disposed centrally thereof near its lower end and which 45 communicates with the opening 3 centrally of the bottom wall thereof, and also opens in the furcation 5 of the bifurcated lower end 6, of the body portion 2.

The furcation 5, of the bifurcated lower 50 end 6, of the body portion 2, in connection with the slot 4, provides transverse shoulders 7, 8, and inclined bearing surfaces 9, 10.

The upper wall of the opening 3, is rounded and secured thereagainst by the hold-fast 55 device 11, is a substantially yoke-shaped

spring 12, normally having the ends 13, thereof projecting toward each other.

Intersecting the bifurcated lower end 6 of the body portion 2, is a pair of transverse openings 13', 14, through which extend pivot 60 pins 15.

Mounted upon the pins 15, are oppositely disposed counterbalanced cutters, and each of which comprises a segment shaped head 16, permanently disposed below the lower 65 end of the body portion 2, and formed with inclined tops 17, which normally abut against the bevel portion 18 formed on the lower end of the body portion 2.

The heads 16 are oppositely disposed and each of which has formed integral centrally of its top, a flat shank 19, having an enlarged lower portion eccentrically mounted on a pin 15. The shank 19, has a squared shoulder 20, and a rounded shoulder 21. 70 The latter abuts against the shoulder 9, and the former engages the bearing surface 7. The upper portion of each of the shanks 19, is tapered as at 22, and inset with respect to the enlarged lower portion of the shank 19. 80 The tapered upper portions of the shanks 19, when the cutters are in normal position abut, and the upper ends of said tapered portions permanently extend into the spring 12, between the arms 13 thereof whereby said arms 85 will bear against the tapered upper portions 22, and in accordance with the weight of the heads 18 normally maintain the cutters projected.

In Fig. 2 of the drawings, the casing or 90 pipe is indicated at 23, and the diameter of the casing is such that it engages the heads 16, and cutters shift them inwardly whereby the upper ends of the shanks 19, are moved apart against the action of the 95 spring 12.

Each of the heads 16, has its periphery throughout upon the arc of a circle, from the top to the bottom of the head, as at 25, to prevent any possibility of binding between the periphery and the inner face or joints of the casing when inserting the same therethrough.

What I claim is:

A reamer provided with a body portion 105 having an opening, a yoke-shaped spring secured therein and having the legs thereof normally extending toward each other, said body portion having a bifurcated lower end and further having a lengthwise opening 110

communicating with a horizontal opening and with the furcation of said end, the walls of said lengthwise opening forming inclined bearing surfaces and the top wall of said furcation provide flat shoulders, shanks eccentrically pivoted in the bifurcated end of said body portion and extending into the horizontal opening and between the legs of said

spring, said shanks provided with rounded and flat shoulders engaging the bearing surface and shoulders of the body portion, and cutter heads carried by the shanks and arranged exteriorly of the body portion. 10

In testimony whereof I affix my signature.

CHARLES L. DUNHAM.
